PORTABLE TOILET FOR CHILDREN

Application filed October 31, 1927. Serial No. 229,871.

This invention relates to portable toilets for children.

An object of the invention is to provide a portable structure, more especially designed for use in connection with automobiles, and of such character that, under ordinary conditions, the structure may be used as a spare seat, and when occasion arises may be used by children as a toilet.

Another object of the invention is to provide a structure of this character, including a receptacle which is ordinarily concealed from view, and which is rigidly, but detachably, maintained in position, and made readily accessible by lifting a hinged cover.

Still another object of the invention is to provide, in a structure of this character, a receptacle which may be sealed, together with means for introducing liquid into the receptacle to facilitate cleaning thereof.

Other and further objects and advantages of the invention will more fully and clearly appear from the description and claims hereinafter following.

In the drawings forming a part of this specification, Figure 1 is a perspective view of the structure, showing the same in condition to be used as a spare seat. Figure 2 is a perspective view of the structure, showing the cover raised, and adapted for use as a toilet. Fig. 3 is a rear elevational view of the structure, showing a hinged door through which access may be gained to the receptacle for the purpose of removing or inserting the same, with respect to the structure. Fig. 4 is a top plan view of the structure, with the cover and top portion omitted to more clearly show the interior arrangement thereof. Fig. 5 is a vertical sectional view corresponding substantially to the line 5—5 of Fig. 4. Fig. 6 is a vertical sectional view corresponding to the line 6—6 of Fig. 4. Fig. 7 is a fragmentary sectional view of the pump arrangement utilized in connection with the invention and corresponds to the line 7—7 of Fig. 4. Fig. 8 is a fragmentary sectional view corresponding to the line 8—8 of Fig. 4 and showing the filling conduit for the water tank. Fig. 9 is an enlarged detail view of a cover for the receptacle. Fig. 10 is an enlarged sectional

view of the door through which the receptacle is inserted and removed.

As shown in the drawings, the structure comprises a front wall 10, side walls 11 and 12, and rear wall 13, all of said walls being formed of sheet metal, and bent to provide a rectangular formation tapering from the bottom upwardly. Each of said walls is cut out, as indicated at 14, to provide supporting feet 15—15, one at each corner of the structure. The upper edges of the walls 10, 11, 12 and 13, are bent over to provide in-turned annular flanges, 16, 17, 18 and 19, and upon these flanges is secured a seat portion 20, by means of suitable bolts, said seat portion being provided with an annular centrally disposed aperture 21. Hinged to the rear edge of said portion 20 is a cover or auxiliary seat 22, suitable hinges being indicated at 23. The cover 22, upon its end surface, adjacent the rear edge thereof, has secured thereto curved arms 24—24 which are receivable in slots 25—25 in the cover portion 20, the lower ends of the arms being provided with suitable pins 26 which limit the outward swinging movement of the cover 22. The cover 22 is provided with a cushion on its outer surface, indicated at 27. Means are provided for locking the cover 22 in closed position, said means including a keeper 28 on the cover, and a sliding bolt 29 mounted upon the front wall 10 of the structure, said bolt being provided with a lateral extension 30 adapted to project upwardly through the opening 31 in the seat 20, said projection being adapted to engage with a shoulder 32 in the keeper, after the bolt 29 has been inserted and rotated to cause such engagement.

In the lower end of the structure is mounted a sheet metal tank, indicated at 33, said tank being held in position by suitable brackets 34—34, the upper wall 35 of the tank serving to define the bottom of the compartment in the structure in which the receptacle 36 is disposed, the remaining walls of the compartment being defined by the upper portions of the walls 10, 11 and 12 and the seat 20.

The receptacle 36 is annular in form and provided with a suitable handle 37. The

upper annular wall of the receptacle terminates in a laterally extending annular flange 38. The receptacle is of a character which may be obtained in the open market. A lid 360 is provided for the receptacle, which has a deep annular flange 361 which fits into the receptacle and substantially seals the same when the lid is in position, said lid having a depression to accommodate the fingers of the user, a handle 362 being provided which lies substantially flush with the remaining body portion of the lid 360. Means are provided for maintaining the receptacle 36 in position, said means including a sheet metal bracket 39 secured to the flange 17 on the front wall 10, a sheet metal bracket 40, secured to the flange 16 on the wall 11, and a sheet metal bracket 41, secured to the flange 18 on the wall 12, said brackets being spaced some distance from the under surface of the seat 20. The flange 38 of the receptacle 36 is slid between the brackets 39, 40 and 41 and the under surface of the seat 20, a fabric pad 42 being secured to the under surface of the seat 20 and bearing upon the top of the flange 38, when the receptacle 36 is in position. The receptacle 36 is adapted to be inserted and removed from the structure by way of a hinged door 43 at the rear of the structure. The rear wall 13 is provided with an opening 44, through which the receptacle 36 is inserted or removed, said opening being closed by the door 43. The door 43 is provided with a spring latch 45 normally urged outwardly by a spring 46, said latch being adapted to enter a recess 47 in the seat 20, as best shown in Fig. 6 and Fig. 10, said latch being adapted to be retracted by a handle 48, which depresses the latch 45 so that the door may be opened, the door being automatically locked when the same is swung to closed position. The inner surface of the door is provided with a rack 49, having side, front and bottom walls defining a pocket 50 for a plurality of sheets of paper, indicated at 51. Secured to the forward wall of the pocket 50 is a pair of spring arms 52-52, the free extremities of which are adapted to bear upon the receptacle 36, as best shown in Figs. 4 and 6, the spring arms being connected together at their inner ends by means of a connecting portion 53, the latter being secured as by welding to the front wall of the pocket 50.

Means are provided for introducing liquid into the receptacle 36, said means including a tube 54 having its upper end mounted in the seat portion 20, while the lower end thereof extends downwardly through the nipple 55 in the top wall 35 of the tank 33, and the lower end of the tube 54 is disposed in a well 56 at the bottom of the tank, the lower end of the tube being provided with inlet openings 57, to admit the liquid from the main body portion of the tank 33. A nozzle or spout 57 is provided adjacent the upper end of the

tube 54, which is so disposed as to conduct water from the tube 54 into the receptacle 36. Mounted in the tube or cylinder 54 is a piston head 58 which is provided with an inlet opening 59, closed by ball valve 60. The piston head 58 is operated by a piston rod 61 extending, at its upper end, through a bushing 62, and terminating in an operating handle 61-A, by manipulation of which the piston rod may be reciprocated to raise the liquid in the cylinder 54 and discharge the same into the receptacle 36. The tank 33 is provided with a filler tube 63, having its upper end mounted in the seat portion 20, a detachable filler cap 64 being provided to permit filling of the tank.

By the above described arrangement it will be appreciated that a convenient portable toilet is provided especially adapted for the use of children, and in connection with automobiles, the structure being of such character that, under ordinary conditions, it may be used as a spare seat. When intended for use as a toilet, the cover 22 may be raised and the lid 360 removed. Liquid may be injected into the receptacle before and after use as desired. When the lid 360 is replaced the receptacle is sealed, the cover 22 lowered and locked in position, so that the device is again utilizable as a spare seat. The receptacle is maintained against vibration or displacement by the members engaging the flange of the receptacle and the spring fingers which bear thereon. The receptacle 36 may be inserted and removed with respect to the structure, through the rear door 43, being detachable and engageable with the holding means by movement in opposite directions through the door opening, the brackets 39, 40 and 41 being so arranged as to permit this movement, and when the receptacle is in its compartment in the structure the spring fingers 52-52 on the door bear thereon and aid in maintaining the receptacle in proper position.

While we have herein shown and described what we now consider the proper manner of carrying out our invention, the same is merely illustrative, and we contemplate all changes and modifications that come within the scope of the claims appended hereto.

We claim:

1. In a convertible spare seat and toilet device, the combination with upstanding walls providing a hollow enclosure, said enclosure having a main seat at its top formed with an opening and said enclosure having a side door opening thereinto; a receptacle adapted to be inserted into said enclosure through said door or removed from said enclosure through said door, as desired, said receptacle having a lid provided with means cooperating with the receptacle to seal the same when the lid is in position with respect thereto, said lid being

removable and replaceable through the top opening in said main seat when the device is used as a toilet, and said receptacle being removable with reference to said enclosure with the lid in sealing position, through said door, when the receptacle is to be emptied; holding means for detachably maintaining said receptacle in position with respect to the opening in the main seat; and a hinged auxiliary seat adapted to conceal the main seat, said auxiliary seat being detachably connected to said enclosure and therewith providing a spare seat when not used as a toilet.

2. In a convertible spare seat and toilet device, the combination with a support providing a hollow enclosure, said support having a main seat at its top formed with an opening and said enclosure having a side door opening thereinto; a receptacle adapted to be inserted into, and removed from, said enclosure through said door, said receptacle having a lid provided with means cooperating therewith to seal the receptacle when the lid is in position, said lid being removable and replaceable through the top opening in said main seat when the device is used as a toilet, and said receptacle with the lid in sealing position being removable through said door when the receptacle is to be emptied; holding means for detachably maintaining said receptacle in position within said enclosure and with respect to the opening in the main seat; a tank arranged within said enclosure; a tube extending from said tank and having a nozzle disposed in position to discharge into said receptacle when the latter is in position in said enclosure; a pump disposed within said enclosure and operable to draw liquid from said tank and discharge the same through said nozzle into said receptacle; and an auxiliary seat fitted over the main seat and detachably connected therewith, said auxiliary seat in conjunction with said enclosure providing a spare seat when the device is not in use as a toilet.

In witness that we claim the foregoing we have hereunto subscribed our names this 27th day of October 1927.

CHRIS F. PFISTERER.
